[57] CLAIM

The ornamental design for an ignition wire separator for engines, as shown and described.

DESCRIPTION

FIG. 1 is a top plan view of an ignition wire separator for engines embodying the invention design;

FIG. 2 is a bottom plan view thereof;

FIG. 3 is a side elevational view thereof looking from the bottom of FIG. 1; and

FIG. 4 is a side elevational view thereof looking from the right side of FIG. 1.

FIG. 1

FIG. 2

FIG. 3

FIG. 4
